GLASS CRUET OR SIMILAR ARTICLE

T. Clarence Heisey, Newark, Ohio, assignor to
A. H. Heisey & Company, Newark, Ohio

Application January 26, 1950, Serial No. 7,477

Term of patent 14 years

(Cl. D36—2)

To all whom it may concern:

Be it known that I, T. Clarence Heisey, a citizen of the United States of America, and a resident of Newark, in the county of Licking and State of Ohio, have invented a new, original, and ornamental Design for a Glass Cruet or Similar Article, of which the following is the specification, reference being had to the accompanying drawing forming a part hereof:

Figure 1 is a side elevational view of a glass cruet or similar article showing my new design.

Figure 2 is a front elevational view of the article shown in Figure 1.

Figure 3 is a top plan view of the article with the stopper removed therefrom.

Figure 4 is a sectional view taken along line 4—4 of Figure 2.

I claim:

The ornamental design for a glass cruet or similar article, substantially as shown.

T. CLARENCE HEISEY.
